Fortsch

[11] Patent Number: Des. 280,597

[45] Date of Patent: ** Sep. 17, 1985

[54] CLAMPING BASE FOR CABLE CLAMPS OR
THE LIKE

3,913,876 10/1975 McSherry 248/73
4,125,240 11/1978 Heard 248/73

[75] Inventor: William A. Fortsch, Bernardsville,
N.J.

Primary Examiner—B. J. Bullock
Attorney, Agent, or Firm—Robert M. Rodrick; Salvatore
J. Abbruzzese

[73] Assignee: Thomas & Betts Corporation,
Raritan, N.J.

[57] CLAIM

[**] Term: 14 Years

The ornamental design for a clamping base for cable
clamps or the like, as shown and described.

[21] Appl. No.: 466,394

DESCRIPTION

[22] Filed: Feb. 14, 1983

FIG. 1 is a top perspective view of a clamping base for
cable clamps or the like showing my new design, the
cable clamp being shown in broken lines for illustrative
purposes only;

[52] U.S. Cl. D8/396; D8/394
[58] Field of Search D8/382, 394-396;
248/73; 24/16 PB

FIG. 2 is a top plan view thereof;

FIG. 3 is a front elevational view thereof, the rear being
a mirror image;

FIG. 4 is a side elevational view thereof;

FIG. 5 is a bottom plan view thereof.
